UNITED STATES PATENT OFFICE.

JUSTUS R. KINNEY, OF DORCHESTER, MASSACHUSETTS.

STARTING DEVICE FOR MOTOR-CARS.

1,077,884.

Specification of Letters Patent.

Patented Nov. 4, 1913.

Application filed May 29, 1911. Serial No. 630,537.

To all whom it may concern:

Be it known that I, JUSTUS R. KINNEY, a citizen of the United States of America, and a resident of Dorchester, in the county of 5 Suffolk and State of Massachusetts, have invented certain new and useful Improvements in Starting Devices for Motor-Cars, of which the following is a specification.

This invention relates to starting devices, 10 and particularly to starting devices which are used in connection with motor cars.

The object of the present invention is to provide a device which may be actuated by compressed air or other fluid to cause an initial rotation to the engine shaft and thus dispense with the usual cranking.

The invention consists in providing a supplemental shaft in alinement with the engine shaft, which supplemental shaft is 20 adapted to reciprocate to engage with the engine shaft by means of suitable clutch mechanisms, and is adapted subsequently to be oscillated while in engagement with the engine shaft to impart to the latter an initial rotation.

The invention consists further in mechanism for reciprocating and oscillating said actuating shaft by means of fluid pressure under control of the chauffeur.

30 The invention further consists in means for returning said actuating shaft to its normal position after the initial rotation has been imparted to the engine shaft.

The invention further consists in certain 35 novel features of construction and arrangement of parts which will be thoroughly understood by reference to the description of the drawings and to the claims hereinafter given.

40 Of the drawings: Figure 1 represents a section of a starting device embodying the features of the present invention and showing the clutch mechanism in elevation. Fig. 2 is a section of the same, the cutting plane 45 being on line 2—2 on Fig. 1, showing in elevation a portion of a compressed air tank applied thereto. Fig. 3 is a section of the same, the cutting plane being on line 3—3 on Fig. 1. Fig. 4 represents a partial transverse section of the same, the cutting plane being on line 4 on Fig. 2. Fig. 5 represents a partial transverse section of the same, the cutting plane being on line 5 on Fig. 2, and Fig. 6 represents a section of the controlling 55 valve.

Similar characters designate like parts

throughout the several figures of the drawings.

In the drawings, 10 represents a cup-shaped member provided with a cylindrical chamber 11, said cup-shaped member 10 being secured to a rear plate 13 by means of a plurality of bolts 14 passing through a flange 15 formed upon said cup-shaped member. The rear plate 13 is secured in a fixed position in any well-known manner, as, for instance, by means of screws engaging the threaded openings 16 in the lugs 17 formed upon said rear plate 13. An actuating shaft 18, mounted in suitable bearings formed in the said cup-shaped member 10 and said rear plate 13, is positioned within the center of said chamber 11. The outer end of said actuating shaft 18 is squared as indicated at 19 to receive a crank whereby the shaft 18 may be actuated in the usual manner when desired. The opposite end of said shaft 18 has secured thereto a clutch member 20 and in alinement with said shaft 18 is an engine shaft 21 having secured to its end a coacting clutch member 22. These clutch members 20 and 22 are normally separated by means of a spring 23 acting upon one face of a piston 24 secured to or formed upon the shaft 18 and mounted in a cylindrical chamber 25 formed in the back plate 13, said piston chamber being preferably of less diameter than the chamber 11. The forward movement of the piston 24, by the action thereon of the spring 23, is limited by the hub of the clutch member 20 contacting with the closing cap 26 of the chamber 25 so that a compartment 27 is always left between the forward face of the piston 24 and the inner end of the piston chamber 25. Communicating with the compartment 27 is a passage 28 formed in the back plate 13, from the outer end of which extends a supply pipe 29 communicating with the compressed air tank 30. At a suitable point in the line of pipe 29 so that it is readily accessible to the chauffeur is a three-way valve 31, which is of any well-known construction, and is normally closed. Extending from the compartment 27 is another passage 32 smaller than the passage 28, this passage 32 communicating through an opening 33 with the chamber 11. Within the chamber 11 and keyed to the shaft 18 in such a manner as to permit a reciprocating movement of said shaft, is a piston member 34, the opposite faces of which bear respec-

tively against the inner faces of the cup-shaped member 10 and the rear plate 13. Secured to or formed upon the piston member 34 is a segmental blade 35, the outer wall of which contacts with the cylindrical inner wall of the chamber 11. Secured to the cup-shaped member by means of bolts 36 and by means of a bolt 37 extending through both said cup-shaped member 10 and the 5 rear plate 13, is a segmental abutment 38, the inner wall of which contacts with the periphery of the piston member 34. The uncovered radial walls of the abutment 38 are provided with buffers 39 and 40 of rubber or any other suitable resilient material. 10 The buffer 39 extends sufficiently beyond the face of the abutment 38 to prevent the opening 33 being closed at any time when the blade 35 is in its normal position, as indicated in Fig. 2 of the drawings. The piston member 34 is provided with a recess 41 in which is positioned a helical spring 42, one end of which engages a lip 43 formed upon or secured to the piston member 34, 15 while the opposite end is fastened to a pin 44 rigidly secured in the cup-shaped member 10.

The operation of the invention is as follows:—The various movable parts of the 20 device are normally in the positions shown in Figs. 1 and 2 of the drawings. The supply tank 30 is normally filled with air or other fluid and under pressure while the valve 31 is normally closed. When it is desired to impart a rotary movement to the engine shaft 21 to start the engine the chauffeur opens the valve 31, permitting the air or other fluid contained within the tank 30 to pass through the pipe 29 into the compartment 27. Owing to the contracted discharge opening from this compartment 27 a greater supply of air is admitted thereto than can immediately be discharged therefrom. This results in the compressed air 25 acting upon the piston 24 to move it and the actuating shaft 18 against the tension of the spring 23 toward the clutch member 22, so that the clutch member 20 on said actuating shaft 18 will engage therewith. In 30 the meantime during this movement of the actuating shaft 18 to engage with the engine shaft 21 by means of the two part clutch mechanism 20 and 22 the compressed air being supplied from the tank 30 to the compartment 27 is passing through the passage 32 and opening 33 into the space 46 between the abutment 38 against the blade 35 of the piston member 34. This continued pressure admitted to the space 46 will cause 35 the blade 35 with the piston member 34 of which it forms a part to be moved in the direction of the arrow *a*. The piston member 34 with its blade 35 will continue to move about the axis of the actuating shaft 40 causing a partial rotation of said shaft until

the blade 35 is limited in its movement in this direction by coming into contact with the buffer 40 on the abutment 38. Any air in advance of the blade 35 during this movement is permitted to escape through the 45 vent 45 which is located a short distance from the buffer 40. When the blade 35 has passed this vent 45, an air cushion will be formed in advance of the blade to retard its movement and prevent undue shock when its further movement is finally limited by contact with the buffer 40. As soon as the engine shaft 21 completes a revolution the valve 31 is operated to shut off the admission of further compressed air from the tank 30, the valve plug being moved in the direction of the arrow *b* on Fig. 6, so that the passage 47 therethrough will be horizontal and communicate with the vent 49 in the valve casing while the branch passage 48 will communicate with the pipe 29 leading to the compartment 27. The spring 42 will then be free to actuate the piston member 34 in a reverse direction to bring it to its normal position while the spring 23 will act 50 on the piston 24 to separate the clutch members 20 and 22. When the parts are returning to their normal positions the fluid in advance will be forced through the various passages and be ejected from the vent outlet 49. When the parts have assumed their normal positions the starting device is ready to repeat the operation.

It is believed that the operation and many advantages of the invention will be thoroughly understood from the foregoing.

Having thus described my invention, I claim:

1. In a device of the class described, the combination of two normally separated alined shafts; coacting devices thereon for temporarily connecting said shafts; a piston and a blade on one of said shafts; and means for applying pressure against said piston to temporarily connect said shafts and subsequently against said blade to cause a partial rotation of said shaft.

2. In a device of the class described, the combination of two normally separated alined shafts; coacting devices thereon for temporarily connecting said shafts; a piston and a blade on one of said shafts; means for applying pressure against said piston to temporarily connect said shafts and subsequently against said blade to cause a partial rotation of the bladed shaft; and means in the path of said blade to limit its rotary movement.

3. In a device of the class described, the combination of two normally separated alined shafts; coacting devices thereon for temporarily connecting said shafts; a piston and a blade on one of said shafts; means for applying pressure against said piston to temporarily connect said shafts and subse-

quently against said blade to cause a partial rotation of the bladed shaft; and means for reversely rotating said bladed shaft to its normal position.

5. In a device of the class described, the combination of two normally separated alined shafts; coating devices thereon for temporarily connecting said shafts; a piston and a blade on one of said shafts; means for applying pressure against said piston to temporarily connect said shafts and subsequently against said blade to cause a partial rotation of said bladed shaft; and a spring for reversely rotating said bladed shaft to its normal position.

6. In a device of the class described, the combination of two alined shafts one of which is adapted to be reciprocated; a clutch mechanism interposed between the opposed ends of said shafts; a casing; a piston therein on one of said shafts; a spring surrounding said piston shaft and acting on said piston to retain said clutch mechanism in inoperative position; means for applying pressure to the opposite face of said piston to move said piston shaft endwise and cause said clutch mechanism to connect said shaft; a radial blade on said piston shaft; and means whereby pressure may be applied to said blade for rotating said piston shaft about its axis.

7. In a device of the class described, the combination of two alined shafts one of which is adapted to be reciprocated; a clutch mechanism interposed between the opposed ends of said shafts; a casing; a piston therein on one of said shafts; a spring acting thereon to retain said clutch mechanism in inoperative position; means for applying pressure to the opposite face of said piston to move said piston shaft endwise and cause said clutch mechanism to connect said shafts; a radial blade on said piston shaft; means whereby pressure may be applied to said blade for rotating said piston shaft about its axis; and means for limiting the rotation of said shaft.

8. In a device of the class described, the combination of two alined shafts one of which is adapted to be reciprocated; a clutch mechanism interposed between the opposed ends of said shafts; a casing; a piston therein on one of said shafts; a spring acting thereon to retain said clutch mechanism in inoperative position; means for applying pressure to the opposite face of said piston to move said piston shaft endwise and cause said clutch mechanism to connect said shafts; a radial blade on said piston shaft; means whereby pressure may be applied to said blade for rotating said piston shaft about its axis; and means for rotating said shaft in the reverse direction to its normal position.

9. In a device of the class described, the

combination of two alined shafts; a clutch mechanism interposed between the opposed ends of said shafts; a casing; a piston therein on one of said shafts; a spring acting thereon to retain said clutch mechanism in inoperative position; means for applying pressure to the opposite face of said piston to move said piston shaft endwise and cause said clutch mechanism to connect said shafts; a radial blade on said piston shaft; means whereby pressure may be applied to said blade to rotate said piston shaft about its axis; and means in the path of said blade to limit the rotation of said shaft.

10. In a device of the class described, the combination of two alined shafts; a clutch mechanism interposed between the opposed ends of said shafts; a casing; a piston therein on one of said shafts; a spring acting thereon to retain said clutch mechanism in inoperative position; means for applying pressure to the opposite face of said piston to move said piston shaft endwise and cause said clutch mechanism to connect said shafts; a radial blade on said piston shaft; means whereby pressure may be applied to said blade for rotating said piston shaft about its axis; and a buffer in the path of said blade to limit the rotation of said shaft.

11. In a device of the class described, the combination of two alined shafts; a clutch mechanism interposed between the opposed ends of said shafts; a casing; a piston therein on one of said shafts; a spring acting thereon to retain said clutch mechanism in inoperative position; means for applying pressure to the opposite face of said piston to move said piston shaft endwise and cause said clutch mechanism to connect said shafts; a radial blade on said piston shaft; means whereby pressure may be applied to said blade for rotating said piston shaft about its axis; means in the path of said blade to limit the rotation of said shaft; and a helical spring for returning said shaft to its normal position.

12. In a device of the class described, the combination of two alined shafts; a clutch mechanism interposed between the opposed ends of said shafts; a fixed casing provided with two cylindrical chambers of different diameters connected by a contracted passage; a piston secured to one of said shafts and positioned in the smaller chamber; a spring acting upon one face of said piston; means for admitting fluid to said piston chamber through a passage of larger diameter than said contracted passage to act upon the opposite face of said piston; and a radial blade on said piston shaft adapted to be actuated by the inflow of fluid into said larger chamber to rotate said shaft.

13. In a device of the class described, the combination of two alined shafts; a clutch mechanism interposed between the op-

posed ends of said shafts; a fixed casing provided with two cylindrical chambers of different diameters connected by a contracted passage; a piston secured to one of said shafts and positioned in the smaller chamber; a spring acting upon one face of said piston; means for admitting fluid to said piston chamber through a passage of larger diameter than said contracted passage to act upon the opposite face of said piston; a radial blade on said piston shaft adapted to be actuated by the inflow of fluid into said larger chamber to rotate said shaft; and an abutment in said larger chamber to limit the movement of said blade in either direction.

13. In a device of the class described, the combination of two alined shafts; a clutch mechanism interposed between the opposed ends of said shafts; a fixed casing provided with two cylindrical chambers of different diameters connected by a contracted passage; a piston secured to one of said shafts and positioned in the smaller chamber; a spring acting upon one face of said piston; means for admitting fluid to said piston chamber through a passage having a larger area than said contracted passage to act upon the opposite face of said piston; a radial blade on said piston shaft adapted to be actuated by the inflow of fluid into said larger chamber to rotate said shaft; and an abutment provided with yielding buffers in said larger chamber to limit the movement of said blade in either direction.

14. In a device of the class described, the combination of two alined shafts; a clutch mechanism interposed between the opposed ends of said shafts; a fixed casing provided with two cylindrical chambers of different diameters connected by a contracted passage; a piston secured to one of said shafts and positioned in the smaller chamber; a spring acting upon one face of said piston; means for admitting fluid to said piston chamber through a passage having a larger area than said contracted passage to act upon the opposite face of said piston; a radial blade on said piston shaft adapted to be actuated by the inflow of fluid into said larger chamber to rotate said shaft; and an abutment in said larger chamber to limit the movement of said blade in either direction; and a vent from said larger chamber near the end of movement of said blade.

15. In a device of the class described, the combination of two alined shafts; a clutch mechanism interposed between the opposed ends of said shafts; a fixed casing provided with two cylindrical chambers of different diameters connected by a contracted passage; a piston secured to one of said shafts and positioned in the smaller chamber; a spring acting upon one face of said piston; means for admitting fluid to said piston

chamber through a passage having a larger area than said contracted passage to act upon the opposite face of said piston; a radial blade on said piston shaft provided with a recess and adapted to be actuated by the inflow of fluid into said larger chamber to rotate said shaft; and a spring in said recess to return said blade to its normal position.

16. In a device of the class described, the combination of two alined shafts; a clutch mechanism interposed between the opposed ends of said shafts; a fixed casing provided with two cylindrical chambers of different diameters connected by a contracted passage; a piston secured to one of said shafts and positioned in the smaller chamber; a spring acting upon one face of said piston; a passage to said piston chamber having an area greater than said contracted passage and adapted to admit fluid to act upon the other face of said piston; a compressed air reservoir; a valved pipe therefrom to said larger passage; and a radial blade on said piston shaft adapted to be actuated by the inflow of fluid into said larger chamber to rotate said shaft.

17. In a device of the class described, the combination of two alined shafts; a clutch mechanism interposed between the opposed ends of said shafts; a fixed casing provided with two cylindrical chambers of different diameters connected by a contracted passage; a piston secured to one of said shafts and positioned in the smaller chamber which has an inlet passage thereto of greater area than said contracted passage; a spring acting upon one face of said piston; means for admitting fluid to said piston chamber to act upon the opposite face of said piston; a radial blade on said piston shaft adapted to be actuated by the inflow of fluid into said larger chamber to rotate said shaft; and an abutment in said larger chamber to limit the movement of said blade in either direction.

18. In a device of the class described, the combination of two alined shafts; a clutch mechanism interposed between the opposed ends of said shafts; a fixed casing provided with two cylindrical chambers of different diameters connected by a contracted passage and the smaller of which has an inlet thereto of a greater area than said connecting passage; a piston secured to one of said shafts and positioned in the smaller chamber; a spring acting upon one face of said piston; means for admitting fluid to said piston chamber to act upon the opposite face of said piston; a radial blade on said piston shaft adapted to be actuated by the inflow of fluid into said larger chamber to rotate said shaft; and an abutment provided with yielding buffers in said larger chamber to limit the movement of said blade in either direction.

19. In a device of the class described, the combination of two alined shafts; a clutch mechanism interposed between the opposed ends of said shafts; a fixed casing provided with two cylindrical chambers of different diameters connected by a contracted passage and the smaller of which has an inlet thereto of a greater area than said connecting passage; a piston secured to one of said shafts and positioned in the smaller chamber; a spring acting upon one face of said piston; means for admitting fluid to said piston chamber to act upon the opposite face of said piston; a radial blade on said piston shaft adapted to be actuated by the inflow of fluid into said larger chamber to rotate said shaft; an abutment in said larger chamber to limit the movement of said blade in either direction; and a vent from said larger chamber near the end of movement of said blade.

20. In a device of the class described, the combination of two alined shafts; a clutch mechanism interposed between the opposed ends of said shafts; a fixed casing provided with two cylindrical chambers of different diameters connected by a contracted passage and the smaller of which has an inlet thereto of a greater area than said connecting passage; a piston secured to one of said shafts and positioned in the smaller chamber; a spring acting upon one face of said piston; means for admitting fluid to said piston chamber to act upon the opposite face of said piston; a radial blade on said piston shaft provided with a recess and adapted to be actuated by the inflow of fluid into said larger chamber to rotate said shaft; and a spring in said recess to return said blade to its normal position.

21. In a device of the class described, the combination of two normally separated alined shafts provided with means whereby they may be temporarily connected, one of which shafts is adapted to be reciprocated; a radial blade on said reciprocating shaft rotatable therewith but adapted for end movement thereon; means for moving said reciprocating shaft endwise by fluid pressure to engage the other; and means for subsequently subjecting said blade to fluid pressure and thereby imparting a rotary movement to said reciprocating shaft.

22. In a device of the class described, the combination of two normally separated alined shafts provided with means whereby they may be temporarily connected, one of which shafts is adapted to be reciprocated; a radial blade on said reciprocating shaft rotatable therewith but adapted for end movement thereon; means for moving said reciprocating shaft endwise by fluid pressure to engage the other; means for subsequently subjecting said blade to fluid pressure and thereby imparting a rotary movement to said reciprocating shaft; and means for limiting the rotary movement of said blade.

23. In a device of the class described, the combination of two alined shafts; a clutch mechanism interposed between the opposed ends of said shafts; a piston on one of said shafts adapted to be acted upon to cause end movement to said shaft and the engagement of said clutch mechanism; a spring acting thereon to retain said clutch mechanism in inoperative position; a radial blade on said piston shaft; and means for subjecting said piston to fluid pressure to cause said clutch mechanism to be engaged and then subjecting said blade to the same fluid pressure to impart to said shaft a rotary movement.

24. In a device of the class described, the combination of two alined shafts; a clutch mechanism interposed between the opposed ends of said shafts; a piston on one of said shafts adapted to be acted upon to cause end movement to said shaft and the engagement of said clutch mechanism; a spring acting thereon to retain said clutch mechanism in inoperative position; a radial blade on said piston shaft; means for subjecting said piston to fluid pressure to cause said clutch mechanism to be engaged and then subjecting said blade to the same fluid pressure to impart a rotary movement to said shaft; and means for limiting the rotation of said piston shaft.

Signed by me at 100 Boylston St., Boston, 100 Mass., this 1st day of May, 1911.
